UNITED STATES PATENT OFFICE.

RAPHAEL ETTER, OF MENAHLGA, MINNESOTA.

BOILER-INSIDE-TUBE CUTTER.

Application filed June 7, 1924. Serial No. 718,563.

The invention provides a tool which is simple in construction and adapted to be manufactured without requiring expensive machinery, and which enables a tube or flue 5 to be quickly cut with the expenditure of a minimum amount of energy.

Other objects and advantages will be apparent and suggest themselves as the nature of the invention is understood.

10 While the drawings illustrate an embodiment of the invention it is to be understood that in adapting the same to meet different conditions and requirements, various changes in the form, proportion and minor details 15 of construction may be resorted to without departing from the spirit of the invention.

Referring to the accompanying drawings forming a part of the application:—

Figure 1 is a side view of a boiler tube 20 cutter embodying the invention; and

Figures 2 and 3 are detail perspective views of opposite ends of the tool showing the same on a larger scale.

Corresponding and like parts are referred 25 to in the following description and designated in the several views of the drawings by like reference characters.

The tool consists of a bar 1 which may be 30 of any length, cross-sectional outline and diameter depending upon the particular work and the size of the tool, it being understood that it is the intention to provide the tool in different sizes. It is proposed to make the tool of black diamond tool steel although 35 any tool steel may be employed, depending upon the cost and nature of the article. The ends of the bar 1 are deflected laterally at opposite angles as indicated at 2 and 3 and

are recurrently inclined in opposite directions as indicated at 4 and 5. The ends of 40 the recurrently inclined portions 4 and 5 are recurved as shown at 4^a and 5^a, respectively, and have their extremities sharpened as shown at 6. The inclined end portions 2 and 3 form cams upon which the bar is 45 rocked whereby to move the cutter laterally and force it through the side of the tube. The two angles enable a person to work on tubes next to the fire-box wall or smoke chamber in fire-box type of boiler, either 50 end being selected as may be found most advantageous.

When using the tool an end portion is inserted within the tube a distance to clear the tube sheet and by moving the outer end 55 of the bar 1 laterally, the cutter within the tube is caused to penetrate the side thereof, and this operation is repeated until the tube or flue is cut.

What is claimed is:—

A boiler tube cutter including a rigid bar of the crow-bar type formed straight throughout the major portion of its length, an end portion of said bar being inclined at an angle to said major portion, the portion of said bar at the end of said inclined portion recurrently inclined relatively to the first mentioned inclined portion and to the major portion aforesaid, and the extremity of the bar recurved and sharpened 70 to a cutting edge, said first mentioned inclined portion forming a fulcrum for operation of the sharpened extremity.

In testimony whereof I affix my signature.

RAPHAEL ETTER.
